UNITED STATES PATENT OFFICE.

WILLIAM D. POMEROY, OF NORWOOD, OHIO, ASSIGNOR TO ALLIS-CHALMERS COMPANY, A CORPORATION OF NEW JERSEY, AND THE BULLOCK ELECTRIC MANUFACTURING COMPANY, A CORPORATION OF OHIO.

DYNAMO-ELECTRIC MACHINE.

No. 922,946.

Specification of Letters Patent.

Patented May 25, 1909.

Application filed July 27, 1906. Serial No. 327,974.

To all whom it may concern:

Be it known that I, WILLIAM D. POMEROY, citizen of the United States, residing at Norwood, in the county of Hamilton and State of Ohio, have invented certain new and useful Improvements in Dynamo-Electric Machines, of which the following is a full, clear, and exact specification.

My invention relates to dynamo-electric machines and particularly to the construction of the rotary element.

The object of my invention is to provide a construction of the rotary element which is particularly adapted for high speeds, such as the rotary field member of a turbo-alternator, and in which all parts particularly the field coils are held firmly in position, and are well ventilated.

My invention consists in the details of construction, and in the combinations and arrangements of parts described in the specification and set forth in the appended claims.

For a better understanding of my invention, reference is had to the accompanying drawings in which—

Figure 1 is a partial elevation of the rotary field member of a turbo-alternator; Fig. 2 is an end view of the same, parts being in section and broken away; Fig. 3 is an enlarged elevation of a portion of the expandable ring employed in my improved construction; and Fig. 4 is a plan view of the same.

Referring now to the figures of the drawing, I have shown at 10 a rotary shaft on which is mounted a cylindrical core 11, shown merely in outline for the sake of clearness. The core 11 is provided with field coils, the end-turns of which are shown at 12 in Figs. 1 and 2. The end-turns of the field coils are spaced apart and are preferably held from each other and from the core by insulating blocks 13, mounted on insulating strips 13^a as is shown in U. S. patent to Dunker 790,485, May 23, 1905. This type

of spacing member permits a good circulation of air between the end-turns. Surrounding the end-turns of the coils at each end of the rotor is a rigid ring 14 made preferably from a steel casting. The purpose of this ring is to prevent the end-turns from being displaced or distorted by centrifugal force at high speeds of rotation. The ring is preferably provided with ventilating openings 15.

Located within the end-turns and engaging inner surfaces thereof, so as to act as a support, is an inner expandable ring 16 also preferably made from a steel casting. Referring particularly to Fig. 4 in which a detail of the inner ring is shown, it is seen that the ring is provided with a large number of transverse cuts or slots 17 extending inward alternately from opposite sides, which slots extend almost entirely across the ring. These slots serve a two-fold purpose, the more important of which is to render the ring 16 expandable, as will be explained. A further purpose of the slots is to render possible a good circulation of air around the end-turns. In this instance the inner surface of the ring 16 is inclined outwardly in both directions from the center, as is shown at 18 and 19 in Fig. 1.

Located on the shaft 10 are two expanding rings 20 and 21, which are provided with inclined outer surfaces, which engage the inclined surfaces 18 and 19 on the inner surface of the ring 16. Extending through the rings 20 and 21 are a plurality of adjusting bolts 22 by means of which the rings can be moved toward or away from each other along the shaft to enlarge or decrease the diameter of the inner expandable ring 16, and thus to regulate the pressure of the end-turns of the coils against the outer ring 14. The rings 20 and 21 may be provided with axial air passages as shown at 23, to permit a good circulation of air.

At 24 is shown an end-plate for protecting the coils and other parts, and for holding in position the outer ring 14 which is preferably notched as shown at 25 to receive the outer edge of the plate 24. The plate 24 is in this case provided with a number of openings 26 for the admission of air into the machine. The end-plate 24, in this case, is held in position by a nut 27 which engages a threaded portion 28 of the shaft.

Thus it is seen that I have provided a structure which is suitable for very high speeds. The construction is simple and consists of few parts which are held firmly in position and are well protected. Furthermore there is a good circulation of air at each end of the machine axially through the end-plate 24, through the rings 20, 21 and 16, around the end-turns, and out through the outer ring 14. Also if desired the core may

be provided with air passageways through which air may be drawn.

I do not wish to be confined to the exact details shown and described but aim in my 5 claims to cover all modifications which do not involve a departure from the spirit and scope of my invention.

What I claim as new and desire to secure by Letters Patent is:—

- 10 1. In a dynamo-electric machine, a core, coils carried thereby, said coils having end turns extending beyond the core, a ring surrounding the end turns, an endless expandible ring within the end turns and in engagement with the latter, and means engaging the inner surface of said endless expandible ring, and serving to expand the same so as to force the end turns outward against the outer ring.
- 15 2. In the rotor of a dynamo-electric machine, a core, coils carried thereby and having end turns projecting beyond the ends thereof, a rigid ring surrounding the end turns, an endless expandible ring within the 25 end turns and in engagement with the latter, said ring having an inclined inner surface, and means comprising a third ring engaging the inclined surface of the expandible ring for expanding the latter so as to force the end turns outward against the outer ring.
- 20 3. In a rotor of a dynamo-electric machine, a core, coils carried thereby, said coils having end turns projecting beyond the core, a rigid ring surrounding the end turns, an 35 endless expandible ring within the end turns and in engagement with the latter, said ring having an inclined inner surface, and means for expanding said endless expandible ring comprising a movable expanding ring in one 40 integral piece and engaging the inclined surface of the expandible ring.
4. In the rotor of a dynamo-electric machine, a shaft, a core, coils carried by the core, said coils having end turns projecting beyond 45 the latter, a rigid ring surrounding the end turns, an endless expandible ring within the end turns and in engagement with the same, said ring having an inclined inner surface, and means for expanding said ring comprising 50 an expanding ring engaging the shaft and the inclined surface of said expandible ring, and a plurality of bolts for shifting said expanding ring.
5. In a rotor of a dynamo-electric machine, a core, coils carried thereby, said coils having end-turns projecting beyond the core at one end thereof, a rigid supporting ring surrounding the end-turns, an endless expandible ring within the end-turns, the inner 55 surface of said ring being inclined or beveled in two opposite directions, a pair of expanding rings having inclined faces engaging the inner surface of said expandible ring, and means for moving said pair of rings to expand the ring on which they bear.

6. In a rotor of a dynamo-electric machine, a core, coils carried thereby, said coils having end-turns projecting beyond the core, a rigid supporting ring in one integral piece surrounding the end-turns, an endless expandible supporting ring within the end-turns, the inner surface of said ring being inclined or beveled in two opposite directions, a pair of expanding rings having inclined faces engaging the inner surface of said expandible ring, and a plurality of bolts or rods for moving the pair of expanding rings toward each other to expand the inner supporting ring to force the end-turns outward against the outer ring.

7. In the rotor of a dynamo-electric machine, a core, coils carried thereby, said coils having end turns projecting beyond the core, a rigid ring surrounding the end turns, an expandible ring within the end turns and in engagement with the latter, said expandible ring being in one integral piece and having an inner surface inclined in opposite directions, and means for expanding said expandible ring comprising two expanding rings 90 engaging the inclined portions of the expandible ring, and bolts extending between said expanding rings for shifting the same.

8. In a rotor of a dynamo-electric machine, a core, coils carried thereby, said coils having end-turns projecting beyond the core at one end thereof, a rigid supporting ring surrounding the end-turns, an endless expandible ring within the end-turns, said expandible ring having its inner surface inclined outward on both sides of its center, a pair of expanding rings resting on the shaft and having outer inclined surfaces in engagement with the inclined portions of the inner surface of the expandible ring, and means for moving said pair of expanding rings axially along the shaft to adjust the pressure of the end-turns on the outer ring.

9. In a dynamo-electric machine, a core, coils carried thereby, said coils having end-turns projecting beyond the ends of the core, a ring surrounding the end-turns, a second ring within the end-turns, said second ring having openings or slots cut in both sides whereby it may be expanded, and means for 115 expanding said second ring.

10. In a rotor, a core, coils carried thereby, said coils having end-turns projecting beyond the ends of the core, a ring surrounding the end-turns, and an expandible ring 120 within the end-turns, said ring having transverse cuts or slots extending inward from opposite sides.

11. In a rotor, a core, coils carried thereby, said coils having end-turns projecting beyond the ends of the core, a ring surrounding the end-turns, said ring having ventilating openings, and a second ring within the end-turns, said last named ring having transverse slots or cuts extending inward from 130

opposite sides whereby it can be expanded and a circulation of air around the end-turns can take place.

12. In a rotor of a dynamo-electric machine, a shaft, a core, coils carried thereby, said coils having end-turns projecting beyond the ends of the core, a ring surrounding the end-turns and having ventilating openings, an inner ring within the end-turns, said ring having transverse slots or cuts extending inward from opposite sides, and having an inclined inner surface, and means on the shaft and engaging the inclined surface of the inner ring for expanding said ring, said means permitting a circulation of air through the said inner ring and around the end-turns of the coils.

13. In a rotor of a dynamo-electric machine, a shaft, a core, coils carried thereby, said coils having end-turns or projections, a rigid ring surrounding the end-turns, said ring having ventilating openings, an inner ring within the end-turns, said ring having an inclined inner surface and having trans-
verse cuts or slots extending inward from opposite sides, expanding rings located on the shaft and having inclined surfaces in

engagement with the inclined inner surface of said inner ring, said expanding rings having ventilating openings, and means for moving said expanding rings axially, to adjust the diameter of said inner ring.

14. In a rotor of a dynamo-electric machine, a shaft, a core, coils carried thereby, said coils having end-turns projecting beyond the core, a rigid ring surrounding the end turns, an inner ring within the end turns, said ring having its inner surface inclined or beveled in opposite directions and having overlapping transverse cuts or slots extending inward from opposite sides, a pair of expanding rings located on the shaft and having inclined or beveled surfaces in engagement with the oppositely inclined or beveled inner surface of said inner ring, and means for shifting said expanding rings so as to force the coils outward against the outer ring.

In testimony whereof I affix my signature, in the presence of two witnesses.

WILLIAM D. POMEROY.
